United States Patent Office.

WILLIAM J. DECKER, OF NYACK, NEW YORK.

Letters Patent No. 87,647, dated March 9, 1869.

IMPROVEMENT IN BLIND AND SHUTTER-FASTENING.

The Schedule referred to in these Letters Patent and making part of the same

To all whom it may concern:

Be it known that I, WILLIAM J. DECKER, of Nyack, in the county of Rockland, and State of New York, have invented a new and improved Blind-Fastening; and I do hereby declare that the following is a full, clear, and exact description thereof, which will enable others skilled in the art to make and use the same, reference being had to the accompanying drawings, forming part of this specification, in which—

Figure 1 represents a side view of my improved blind-fastening.

Figure 2 is a face view of the same.

Figure 3 is a side view of the opposite side shown in fig. 1.

Figure 4 is a plan or top view of the same.

Similar letters of reference indicate corresponding parts.

This invention relates to a new combined apparatus for holding blinds and shutters closed, open or partly open, for locking them safely to the window-frame and sash, and for setting the slats.

The apparatus is of very simple construction, readily applied to old and new blinds, and not liable to get out of order.

The invention consists in the general combination of parts, which are an ordinary catch, an additional fastening-lever, for locking the blind, and for holding it partly open, and a lever and rod, for adjusting the slats, all arranged on one small metal frame, which is fastened to the inner side of the blind.

The invention also consists in the arrangement of a spring, by which both the ordinary catch and the additional lever-catch are held in the desired positions, either open or closed.

The invention also consists in the aforesaid lever-catch being so arranged that it can lock the blind to a pin, which is covered by the lower sash. The shutter can, consequently, not be opened without first raising the lower sash, which may also be locked.

A, in the drawing, represents a window-frame.

B is the lower sash, and

C, the blind or shutter.

To the inner side of the blind is secured, by means of screws, *a*, or otherwise, a cast, or other metal plate or frame, *D*, to which the catches and other devices, that constitute my invention, are secured.

E is a double hook-catch, of ordinary or suitable form, pivoted, by a pin, *b*, to lugs *c*, projecting from the plate *D*, said catch projecting from both sides of the blind as usual, and having a hook at each end, as shown.

Its inner hook, *d*, allows the blind to be fastened to a staple or pin, *e*, that projects from the frame *A*.

F is a spring, fastened to the plate or frame *D*, and acting against a shoulder, *o*, of the catch *E*, so as to throw the inner end of the same down.

To a pin, *f*, which projects from the catch *E*, is pivoted a lever, *G*, which, with its outer end, reaches the spring *F*, while its inner end has an eye, by means of which it can be fastened to one of two pins, *g h*, projecting from the sill of the window-frame.

The outer end of the lever *G* is flattened, so that the spring *F* will hold it down, as in fig. 1, while the spring will also serve to hold it up, as indicated by red lines in fig. 3.

When the blind is to be locked, the lever *G* is fitted upon the pin *g*, and the same is then covered by the sliding sash *B*, or by a folding window, as the case may be. The lever *G* is then locked securely, and cannot be swung up to open the blind, unless the sash is first raised, or the window opened. As long as the lever is thus locked, the catch *E* cannot be opened, as its pin, *f*, is held down by the lever.

The lever *G* may also be used to hold the blind partly open, as in fig. 4, when it is fitted upon the pin *h*.

H is a spring-lever, pivoted by a pin, *i*, to the plate *D*, and fitted under or through a rack-bar or arm, *j*, of the said plate *D*.

By means of a rod, *k*, the lever *H* is connected with the slat-bar *I*, as in fig. 2.

A knob or handle, *l*, is arranged on the spring-lever, *H*. By this means, the slat-bar can be moved up or down, more or less, as may be desired, to hold the slats more or less closed or open.

Notches are arranged on the arm *j*, to lock the lever *H* in any desired position.

Having thus described my invention,

I claim as new, and desire to secure by Letters Patent—

1. The lever *G*, when connected with a blind-fastener, *E*, substantially as described.

2. The spring *F*, when arranged as described, to hold at once the spring-catch *E* and the lever *G*, in the requisite positions, as specified.

3. The combination, with each other, of the plate *D*, catch *E*, lever *G*, spring *F*, lever *H*, and rod *k*, all arranged, combined, and operating substantially as herein shown and described.

Witnesses: WILLIAM J. DECKER.

FRANK BLOCKLEY,

ALEX. F. ROBERTS.
